FUEL FEEDING APPARATUS

Application filed March 5, 1925. Serial No. 13,224.

The invention relates to apparatus for feeding liquids wherein the source of supply is at a comparatively low level while the device is at a higher level and distributes liquid to a lower level by gravity flow; in other words, a pump for raising and delivering liquids, but of the particular type operated by sub-atmospheric pressures for raising liquid to the pump chamber.

Such devices are generally well known in the art and particularly identified as fuel feeding devices such as are employed in connection with automobile engines.

The invention, herein described, relates to such a pump and its particular application to the fuel feeding system of an automobile. It is more particularly directed to the control of suction employed for securing sub-atmospheric pressures in the device.

The most common expedient for securing sub-atmospheric pressures is to connect the vacuum feed with the intake manifold of the engine. It has also become a practice to derive suction from the oil pumping system of the automobile.

In either case, there are variable suctions dependent upon the speed of the engine and the depression in the intake manifold.

Where oil pumps are utilized for maintaining suction effects, the variability is caused by changes in engine speed.

Where the intake manifold is employed, variations occur due to throttling and engine speed. For instance, with a wide open throttle and the engine laboring, there is a low limit of suction in the manifold, whereas with the throttle partially closed, there is an increased depression. Necessarily, the mixture is somewhat affected, according to the dilution through the suction connection, with a vacuum device. Where the suction is induced from the oil pump, an adequate suction may always be attained for high and low speeds, but in prior devices, so far as known, at some sacrifice to the circulation in the oil system.

The suction connection may be made with the oil pump with suitable restrictions, but in designing for this, in order to secure the desired sub-atmospheric condition for low

engine speeds, an unnecessary amount of oil must be circulated.

To correct the above conditions and secure balance conditions for all speeds, is the primary object of the present invention which has, as other objects, a restriction of the oil intake of the pump at low engine speeds—low suction—and at the same time, giving ample flow to the pump for circulation. To provide, in conjunction with the restriction to secure suction at the lowest engine speeds, — lowest suction — an automatic means of increasing the variable flow through the pump, thus giving adequate circulation of oil (in case an oil pump is employed) for all engine speeds.

Finally, the objects may be stated as including a means for securing ample vacuum, pressures on low speeds and all speeds of the engine. To this may be added a compensating arrangement between the suction induced in the manifold and the suction induced by the pumping system.

Referring to the drawings:

Figure 1 is a somewhat diagrammatic view of an engine employing the fuel feeding system.

Figure 2 is a sectional view through the supply tank, and its connections.

Figure 3 is a sectional view through the suction connection manifold.

Figure 4 is a detailed plan view of the parts of Figure 3.

Figure 5 is a vertical section through the inlet side of an oil circulating pump adapted to be employed in practicing the invention, the section being taken on a plane parallel to the plane of the paper and the figure revolving 90° from the position indicated in Figure 1.

Figure 6 illustrates a weighted valve plug in the inlet to the pump.

Figure 7 is a detailed cross section view on line 7—7 of Figure 6.

Figure 8 is a vertical section showing a reversible weighted valve plug, in the inlet to the pump.

The diagrammatic showing of Figure 1, may be considered as embodying the usual elements of an automobile engine which has

an inlet manifold A, a water cooling system including a circulating pump P, an oil circulating pump system including an oil pump O, a carburetor C, a fuel feeding device D, and a fuel supply tank B.

5 The fuel feeding device D, may be of any of the well known types commonly employed in which there is a fuel connection 1, between the device and the fuel tank B, a suction connection 2, by which fuel is drawn up from the tank B, to the vacuum feed D, and a delivery connection 3, to the carburetor C.

As illustrated herein, a suction connection 15 2, communicates with a suction manifold 4, thru suitable nipple 5. This manifold has a chamber 6, with two metered openings. The metered opening 7, is controlled by a valve 8, normally resting on a valve seat 9, and controlling communication through a 20 duct 10, with the intake manifold of the engine.

The metered opening 11, is controlled by a similar valve 12, and a valve seat 13. This 25 valve controls a duct 14, connecting through a nipple 15, with the intake side of the oil pump O. There is also a duct 16, communicating with the intake of the oil pump and the crankcase of the engine.

30 The outlet side of the pump communicates through a duct 17, to the distributing system for lubricating the engine.

It will, of course, be immediately apparent that suction may be derived, as illustrated, 35 through a connection with the oil pump, or it might be secured from any pumping device, as for instance, the water circulating pump or an independent pump, although, as specifically hereinafter described, its 40 special connection with the oil pump has many distinct advantages.

The oil pump O, is here illustrated as of the gear type, although such a type is not essential to the invention. As illustrated, 45 the driving gear has a greater number of teeth than the driven gear. There is particular advantage in this arrangement for oil circulating, in that the high speed ratio maintained, gives a desirable flow which is 50 advantageous in conjunction with the suction connection and permits condensation of the size of the gear pump which is of special advantage in connection with the use on automobiles.

55 The connections for the suction conduit and oil inlet conduit are conveniently provided in a special fitting which consists of a tubular nipple 18, having threaded thereon, a tubular body 19, with a nipple 20, for 60 connection with the suction conduit and a nipple 21, for connection with the oil inlet conduit. This forms an inner chamber 22, and there is a metered suction opening 23, to the chamber. At the lower end of the 65 chamber there is a valve seat 24, controlled

by a valve 25. This valve has a metered opening 26, providing for passage of oil to the pump when the valve 25, is seated and permitting a sufficient flow for the lowest speeds of the engine. It is relatively larger 70 than the metered opening 23, of the suction connection and there is thus produced, an adequate suction for operating the fuel feed, at the lowest engine speeds and, at the same time, there is provision for sufficient flow 75 of oil for lubrication.

As illustrated in Figure 5, the valve 25, is weighted by a spring 27, while in Figure 6, a valve member is made of a specified weight and thus used without a spring. The 80 body of the valve 29, above its seat, is cut away to provide ducts 28, so that, as the valve is raised from its seat, there will be a flow through these ducts as well as through the metered opening 26.

The arrangement of parts in Figure 6, is substantially identical with those of Figure 5, with the exception of the omission of the spring 27.

The weight of the valve plug 29, is sufficient to hold it to its seat 30, upon low suction or low engine speed and it will rise according to the pull induced upon it as the pump accelerates, always settling back toward its seat as the speeds decrease.

85 The principle of operation is the same, whether the valve of Figure 5, or Figure 6, is employed.

On low engine speeds, a lubricant will be drawn through the valve opening 26, of the valve plug 25, or the valve opening 31, of the valve plug 29. The flow produced through this orifice will be sufficient to induce adequate suction in the suction connection 14, for operating the feed device D.

100 As the speed increases, the valve will be raised from its seat, permitting a flow of additional lubricant through the ducts 28, about the valve seat 24. This additional flow, of course, induces a somewhat higher 110 suction in the conduit 14, and also gives adequate supply of oil for lubricating purposes. In other words, there is a balanced condition wherein the proper amount of oil may 115 always be fed, even at the lowest speeds, for inducing sufficient suction for operating the vacuum feed device D, without over circulation of oil, and the increased flow for high engine speeds will be automatically regulated according to the speed over that of the 120 minimum required.

125 The manifold 4, in the suction line, has certain advantages in that it gives a connection to the intake manifold and a connection to the oil pump for securing depression to operate the tank D.

In Figure 8, there is illustrated a slightly modified form of weighted valve plug which has particular advantages. This form of the device obviates a necessity of having an oil 130

duct running through the plug, inasmuch as the position of the valve plug upon the valve seat will give requisite automatic compensation to provide for necessary flow at all speeds. Furthermore, the valve plug is 5 made reversible so that in assembling, no error can be made by reversing said plug, as can be done in the plug of Figure 6.

In Figure 8, there is an inlet conduit 43, for connection with a pump and with a 10 metered air opening 44, for the suction connection. The casing of the conduit 43, has provision for attachment of the valve casing 45, and has a valve seat 46, and suitable 15 means of connection 47, for the inlet oil pipe. The weighted valve plug 48, has at both ends, a tapered valve 49, 50. These 20 assume the form of truncated cones and have stop projections 51, 52, extending beyond the taper.

The valve chamber surrounding the valve plug is of sufficient diameter to permit full flow past the valve plug when it is drawn from its seat by the inflowing liquid.

25 The stops 51, 52, limit the upward movement of the valve plug by impinging against the wall 53, at the top of the conduit 43.

Obviously, there will be no restriction in 30 the line between the valve seat 46, and the conduit 43, as ample provision is made for volume about the body of the valve plug 48.

This weighted valve plug 48, serves the 35 purpose; and functions much the same as the plugs heretofore described, although it is of a free-floating type.

When resting upon its seat, and slight suction takes place, it will have a tendency 40 to tilt with its upper portion resting toward the interior wall of the casing 45, thus leaving a sufficient opening about the valve seat 46, for feeding the pump at low speeds.

As the speed increases and a greater flow 45 is required and secured, the valve plug will straighten up and rise from its seat until, at the highest speeds, there is a full opening 50 from the inlet at the valve seat 46, to the conduit 43, said opening permitting a volume or flow equal to the capacity of the conduit 43, and without any undue "wire drawing" effect.

It is apparent that by making the valve 55 plug 48, double ended, it can be reversed without impairing the operation of the device. This is a great aid and makes the device "fool proof" in its assembly. There have been cases in which the plug of Figure 6, has been reversed and its improper functioning has caused defective operation.

Naturally, the drawing over of more or 60 less saturated vapor from a tank B, to the oil circulating system, if in very large volume, causes a certain dilution.

As the vacuum produced by the oil pump 65 is arranged to provide adequate suction at all running speeds, irrespective of the posi-

tion of the throttle, the work upon the oil pump may be relieved whenever the suction of the manifold, due for instance, to partially closed throttle, and high speed, greatly exceeds the requisite suction produced 70 by the oil pump. In such a case, the valve 12, would be closed by the excess suction induced thru the manifold suction and the opening of the valve 8. This would temporarily induce suction for the tank D, and 75 under these conditions, the effect of dilution through the connection 10, would be negligible.

As a convenient means of retaining the ball valves 8 and 12, a spring 8a, having an 80 inturned arm 8b, is snapped into a groove 8c, and thus prevents excessive rise of the ball valves.

From the above, it is apparent there is 85 provided a balance in the suction line which relieves the pump, at excessive speeds and without dangerous dilution, by the connection with the intake manifold.

At low speeds, where suction is taken 90 from the intake manifold, there is often failure of adequate suction for operating the tank D, and this often occurs where the throttle is wide open and the engine is laboring as in "hill climbing". At all such times, the oil pump provides requisite suction to 95 operate the tank D.

This manifold device, with its double suction connection is also of material advantage in conjunction with the tank arrangement herein shown.

To lighten the column of liquid to be 100 lifted to the tank D, from the supply tank B, a metered air opening is provided in the connection.

This metered opening serves a double purpose, namely, that of lightening the column 105 of liquid so that there will be a feed to the tank D, with a comparatively light sub-atmospheric pressure induced through the suction connections, and to prevent flooding whenever the main tank B, is elevated above the feed tank D.

As illustrated in Figure 1, this metered 110 opening is placed at M, within the tank B, near its top, and opens to the feed line 1. In this position, the metered opening is 115 enclosed within the tank, above the liquid level thereof, and free from contamination of dust.

In Figure 2, provision is made for securing 120 advantageous results by applying a T 32, to the upper side of the tank B. This T has a drop tube 33, extending nearly to the bottom of the tank, and a nipple 34, by which it is secured in a flange 35. At the outer end of the T, there is a nipple 36, having a chamber 37, which communicates with a duct 38, through a metered opening 39. A cap 40, secures a dust strainer 41, 125 over the end of the chamber 37.

The chamber 37, may also be packed with suitable material to provide a further straining and cleansing of the air.

There is this advantage in the device of 5 Figure 2, as compared with locating the metered air opening near the top of the tank as in Figure 1.

When the air opening is within the tank the suction induced in the line and tank, 10 above the liquid level, causes more or less dust to enter the gasoline tank and foul the liquid contents thereof.

When the metered air opening is arranged exteriorly of the tank and the air thereto 15 is filtered as is possible with the filter of Figure 2, comparatively no dust particles will be drawn into the tank or its contents. Obviously, any air entering the tank B, will be filtered free from dust.

20 The fuel line 1, is connected to the nipple 42, with the usual expansion type of joint. There are certain advantages in having the metering device exterior to the tank inasmuch as it can be opened and cleansed, if 25 desired, and the chamber 37, affords a means of providing a purifying packing.

Obviously, the exact type of valves and structural forms may be modified to suit the exigencies of any particular requirement, those shown herein being illustrative 30 for the purpose of defining the invention and its scope.

What I claim as my invention and desire 35 to secure by Letters Patent is:

35 1. In a device of the character described, an engine, a reduced pressure fuel feeding device therefor having a liquid fuel supply connection and a suction connection, a pump for circulating a fluid for the engine and 40 producing sub-atmospheric pressures in the suction connection, a manifold interposed in the suction connection between the fuel feeding device and the circulating pump, a connection from said manifold to the intake 45 manifold of the engine, metered valve openings in the manifold, valves automatically controlling the intake manifold connection and the pump connection of the manifold and automatic means including a valve at the intake of the circulating pump permitting circulation of fluid at all times and increase in the flow and consequent suction at the suction connection upon increased speed of the engine and pump.

55 2. In a device of the character described, an engine, a reduced pressure fuel feeding device therefor having a liquid supply connection, a suction connection, a manifold connected therewith, a pump for circulating 60 fluid for the engine and connecting with the manifold at its inlet side, a connection from the manifold to the intake manifold of an engine, metered valve openings and automatic valves controlling the respective connections of the manifold; and automatic

means including a valve at the inlet of the pump for varying the appreciable inlet of the suction of the pumping device and responsive to the suction of the suction connection of the fuel feeding device, upon 70 variations in speed of the engine and pump.
